Primary Examiner — Catherine Tuttle(74) *Attorney, Agent, or Firm* — Levine & Mandelbaum(57) **CLAIM**

The ornamental design for a cosmetic receptacle, as shown and described.

DESCRIPTION

FIG. 1 is a perspective view from the front, right side and top of the cosmetic receptacle showing my new design with the cap element omitted to disclose the underlying parts;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded perspective view including the cap element of the design.

The broken lines in FIG. 7 are included for the purpose of illustrating a portion of the cosmetic receptacle that forms no part of the claimed design.
